UNITED STATES PATENT OFFICE.

OMAR JACOB HOTALING, OF EAST ORANGE, NEW JERSEY.

DISPLAY RACK.

Application filed April 27, 1922. Serial No. 556,934.

To all whom it may concern:

Be it known that I, OMAR J. HOTALING, a citizen of the United States, and a resident of East Orange, in the county of Essex and 5 State of New Jersey, have invented a new and Improved Display Rack, of which the following is a full, clear, and exact description.

This invention relates to display racks 10 which are particularly designed for holding newspapers, magazines or periodicals in display position at news stands.

As an object the invention contemplates an extremely simple and inexpensive display rack which embodies a plurality of correlated elements which are adjustable relative to each other to vary the size of the receiving pockets or the articles to be displayed.

20 As a further object the invention contemplates a display rack of the character described in which the pocket forming elements are capable of being swung to a collapsed or nested position whereby the rack 25 in its entirety will occupy a minimum amount of space when not in use and when it is desirable to transport the same.

With the above recited and other objects in view, the invention resides in the novel 30 construction set forth in the following specification, particularly pointed out in the appended claims and illustrated in the accompanying drawings, it being understood that the right is reserved to embodiments 35 other than those actually illustrated herein to the full extent indicated by the general meaning of the terms in which the claims are expressed.

In the drawing—

40 Figure 1 is a perspective view of a display rack constructed in accordance with the invention.

Fig. 2 is a vertical sectional view therethrough taken approximately on the line 45 2—2 of Fig. 1.

Fig. 3 is an enlarged detail fragmentary view.

Fig. 4 is a horizontal sectional view therethrough taken approximately on the line 50 4—4 of Fig. 3.

Referring to the drawings by characters of reference, the rack embodies a supporting frame which consists of parallel side rails 10 which are connected together by 55 transverse end bars 11. The pocket forming elements consist of a plurality of substan-

tially identical inverted U-shaped members 12 which are preferably constructed from a single length of wire or any other suitable material for the purpose. The side arms 13 of each member 12 are formed at their free extremities with eyes 14 which are aligned with openings 15 in the opposite side rails 10 of the frame to receive the bolts 16 having nuts 17 threaded on their inner extremities 60 for swingingly associating the members 12 with the frame. Each of the side arms 13 are provided with an arcuate rearwardly projecting offset 18 spaced from the eye 14 to register with and receive the shank of the 70 bolt 16 of the next adjacent superposed member 12, which bolt serves as a guide and an additional support for the member 12 as well as a stop for limiting the outward 75 swinging movement of the member due to 80 the engagement of the bight 19 of the offset therewith. When swung to their outermost position, as illustrated, the adjacent members 12 define a plurality of pockets 85 20 which are adapted to receive therebetween the newspapers, magazines, periodicals, or other articles of this character. When swung to their innermost positions, as illustrated in dotted lines in Fig. 2, the members 12 nest one above the other to 90 dispose the same in a plane substantially parallel to the forward edge of the side rails to reduce the thickness of the entire rack to a minimum for storage or transportation. By loosening the nuts 17, the 95 members 12 may be disposed at various relative angular positions to increase or decrease the size of the pockets 20 defined therebetween, the nuts being tightened to retain the members 12 in their adjusted position. 95

From the foregoing it will thus be observed that the bolts 16 in each instance, except the extreme upper and lowermost ones, serve both as a pivot and as a guide and stop for adjacent members 12. It is, 100 of course, understood and appreciated that any number of the members 12 may be employed and that no restriction or limitation as to the construction of the frame is intended. The open end of the offsets 18 at 105 their juncture with the side arms 13 permits of a limited flexing of the members 12 relative to each other.

I claim:

1. A display rack including a plurality 110 of inverted U-shaped members having the free lower extremities of the side legs pivot-

ally connected in superposed relation with a support. the side legs having rearwardly disposed arcuate offsets concentric to the pivotal connection of the legs, said offsets 5 adapted to coact and receive the pivot of the next adjacent superposed member for guiding and bracing said member and for limiting the outward swinging movement of the same whereby said members when in 10 angularly disposed relation define therebetween receiving pockets.

2. A display rack embodying spaced parallel supporting elements, a plurality of inverted U-shaped members having pivotal 15 connection with and disposed between the supporting elements in superposed relation, and means coacting respectively with the pivotal connection of each member and with the member above said pivots for retaining 20 the same in angularly adjusted positions.

3. A display rack embodying spaced parallel supporting elements, a plurality of inverted U-shaped members having the free lower extremities of their side legs pivotally

connected with and between the supporting 25 elements in superposed relation, the side legs having rearwardly disposed arcuate offsets concentric to the pivotal connection of the legs, said offsets adapted to coact and receive the pivot of the next adjacent superposed member for guiding and bracing said member and for limiting the outward swinging movement of the same whereby said members when in angularly disposed relation define therebetween receiving pockets. 30

4. A display rack embodying a plurality of pocket defining elements pivotally connected at their lower extremities in superposed relation on a support, means on each element coacting with the pivotal connection of the next adjacent superposed element for guiding said element in its movement and limiting the outward angular disposition of the same, and means coacting 40 with said pivotal connections for retaining 45 said elements in their adjusted position.

OMAR JACOB HOTALING.
